UNITED STATES PATENT OFFICE.

GEORGES JULES PRAT, OF PARIS, FRANCE.

CHIMNEY DRAFT DEVICE.

Application filed April 27, 1921. Serial No. 464,947.

To all whom it may concern:

Be it known that I, GEORGES JULES PRAT, citizen of the Republic of France, residing at Paris, France, 146 Avenue des Champs Elysees, have invented certain new and useful Improvements in Chimney Draft Devices, of which the following is a specification.

This invention has for its object to facilitate the mounting and dismounting of the rotors of fans employed for producing mechanical draft in chimneys. The invention is characterized by the discharge-spiral of the fan being secured, on the outside or 10 on the inside, to the wall of the chimney, and the rotor and its shaft supported on a frame which is movable in relation to the chimney. This frame is also adapted to 15 carry the mechanism through which the 20 drive is transmitted to the rotor.

The invention is illustrated in the accompanying drawings wherein Figure 1 is a sectional elevation of the base of the chimney stack in which the fan is mounted; and 25 Figure 2 a partial view shewing the rotor dismounted.

The collector or delivery spiral *b* of the fan for producing the draft—either by suction or ejector action—is secured permanently in the wall *a* of the chimney. The rotor *c*, provided with vanes *g*, is supported by a frame *d*, which is preferably guided on slides *e* secured to the ground. This frame bears against the wall *a* of the chimney, the 30 joint being secured by a flanged ring *f* by means of bolts, or in any other similar way, the rotor then occupying its proper position within the spiral.

As is known, the spiral of a fan needs 40 but little attention whereas the rotor, together with its vanes and other moving parts, often needs frequent inspection and repair. My invention enables these operations to be performed without having to 45 undertake the delicate task of dismounting the entire fan in relation to the chimney as, all that is necessary to get at the rotor, is to release the bolts, or other means by which the ring *f* is secured, and the bolts which 50 fasten the frame on the slides, and to with-

draw the rotor from operative position which can be done quickly and without interfering with the functions of the chimney, which can continue to work with natural draft or otherwise, when the aperture is closed by a solid plate in place of the ring *f*.

I am aware that rotary fans have already been constructed in which the rotor is independent from the casing and is adapted to 60 be withdrawn therefrom but what I consider novel is the assemblage of the discharge spiral of such a fan in the wall of a chimney with mechanical draft.

What I claim is:

1. In combination, a chimney, a discharge spiral secured in said chimney, a fan rotor arranged in said spiral, and means wholly supporting said rotor independently of said chimney.

2. In combination, a chimney, a discharge spiral secured in said chimney, a fan rotor arranged in said spiral, and means wholly supporting said rotor independently of said chimney and permitting withdrawal of said 70 rotor from said spiral.

3. In combination, a chimney, a discharge spiral secured in said chimney, a fan rotor arranged in said spiral, and means arranged externally of said chimney and wholly supporting said rotor independently of said chimney.

4. In combination, a chimney, a discharge spiral secured in said chimney, a fan rotor arranged in said spiral, and means arranged externally of said chimney and wholly supporting said rotor independently of said chimney and permitting withdrawal of said 85 rotor from said spiral.

5. In combination, a chimney, a discharge spiral secured in said chimney, and a rotor movable axially through the spiral.

6. In combination, a chimney, a discharge spiral secured in said chimney, a fan rotor arranged in said spiral, and means wholly supporting said rotor independently of said chimney, and permitting the axial withdrawal of said rotor from said spiral.

7. In combination, a chimney, a rotor arranged in said chimney, stationary slides 100

arranged externally of said chimney, and supporting means for said rotor movably mounted in said slides whereby said rotor may be withdrawn from said chimney.

8. In combination, a chimney, a spiral located in said chimney, a fan rotor arranged in said spiral, a ring removably se-

cured to said chimney and arranged at one side of the rotor to provide a closed joint between the latter and said chimney, and means supporting said rotor independently of said ring.

In testimony whereof I affix my signature.

GEORGES JULES PRAT.
